UNITED STATES PATENT OFFICE.

JOSEPH R. HEBERT, OF BROOKLYN, NEW YORK.

DRESS-FORM.

SPECIFICATION forming part of Letters Patent No. 427,510, dated May 6, 1890.

Application filed August 1, 1889. Serial No. 319,478. (No model.)

To all whom it may concern:

Be it known that I, JOSEPH R. HEBERT, a citizen of the United States of America, residing at Brooklyn, in the county of Kings and State of New York, have invented certain new and useful Improvements in Dress or Skirt Forms, of which the following is a description.

My invention relates to dress or skirt forms; and it consists more particularly in the means whereby the form may be adjustably expanded or contracted, and in details of construction and arrangement of parts, as will be set forth in the specification and pointed out in the claims, the object of my invention being to provide a simple and effective means to adjust said form to the various sizes desired.

Referring to the drawings, Figure 1 represents an inside view of my improved form or stand with the sections of the form cut away through a line $x x$, Fig. 2, to more clearly show the adjusting mechanism. Fig. 2 represents a top plan view of the form; and Fig. 3, a top plan view of a detached section of the adjusting mechanism, to be referred to more fully hereinafter.

In the drawings, A represents the standard or post upon which the several parts are supported, and is adapted to be supported in its vertical position by a base or support of any suitable construction.

B represent the sections arranged around and having suitable connection with the post or standard, and adapted to be adjustably expanded or contracted, by means as will hereinafter be described. Said sections consist of two or more vertically-arranged ribs suitably connected by horizontally-arranged tie-pieces, as clearly shown in Figs. 1 and 2, and at their upper ends have connection with supporting-plates C. The said sections are supported and adapted to be expanded and contracted in their relative position to each other and to the central post or standard by two sets of levers, (represented at F and G, respectively.) The upper set of levers, or those adapted to adjust the waist of the form, are fulcrumed at f on an adjustable collar A', located and adapted to be operated on the standard A or a threaded collar thereon, as will be hereinafter described, and are pivotally secured at their upper end to the supporting-plate C or a projection or projections thereon, as shown at d' in Figs. 1 and 2, and at their opposite end engage or embrace the inner edge of a longitudinal slot I, located in one of a series of plates or flanges H, projecting from the standard A or a collar secured thereon. In this instance a tube or covering, as represented at H' in Fig. 3, is located and adapted to be secured in a fixed position on the said post or standard, and from which extend at opposite sides four plates or flanges, (represented at H,) as more clearly shown in said Fig. 3. Each of the said flanges or plates is provided with two longitudinal slots II, arranged at an incline from a point near the center toward the opposite ends, as clearly shown in Fig. 1, and is adapted to be engaged by the inner ends of the two said sets of levers F and G, for the purpose to be hereinafter described. The said lower set of levers G are also fulcrumed on an adjustable collar (represented at A²) located and adapted to operate on the standard A in a position below the said plates or flanges H, the said standard being threaded on its exterior a sufficient distance for the operation of the said adjustable collar, as will be described. The said levers G at their inner or upper ends engage or embrace the edge of the lower slots or openings in the plates or flanges II in substantially the same manner as the upper set F engage the upper slots in said plates H, and at their lower or outer ends said levers G have a pivoted or loose connection with loops or straps a b c d, which have connection with the sides or outer edges of each of the said sections, as clearly shown in Figs. 1 and 2. The standard A is provided with a knob or handle D on its upper end, to enable the same to be turned or revolved to vertically operate the lower collar A' upon the same, as will appear obvious, and the upper collar A' is located in this instance upon an externally-threaded sleeve E', loosely located on the standard and provided with a knob or handle to operate the same.

The operation or manner of adjustment of my improved form is as follows: To adjust the top or waist of the form, the operator, by turning or revolving the threaded sleeve D' by means of its knob or handle E in the proper direction, causes the fulcrum-collar A', located thereon, to ascend, as will appear obvious, thus raising the levers F, secured thereon, and

the inner ends of the latter, engaging the inclined guideways I in the plates or flanges II, are drawn inwardly, or toward the standard A, which serves to throw the upper ends of said 5 levers outwardly to expand the waist or top of the form. The lower part of the form is adjusted in substantially the same manner as the upper part. In this instance, however, the lower fulcrum-collar A² is located on the 10 standard A, as before described, and by turning or revolving the latter to vertically adjust the fulcrum-collar A², located thereon, the lower or outer ends of the levers G are expanded or contracted to adjust the lower part 15 of the form, and the operator is enabled to adjust the form to the desired size by means of a suitable scale located on the plates or flanges H at the side of the inclined guideway therein, in which the ends of the adjusting-levers F 20 operate, as will appear obvious.

Having thus set forth my invention, what I claim as new, and desire to secure by Letters Patent of the United States, is—

1. In a dress-form, the combination, with a 25 central standard and a series of ribs arranged around said standard, of a series of plates or flanges arranged around said standard and provided with inclined guideways, and one or

more series of adjusting-levers centrally pivoted on adjustable collars, connecting with the 30 said guideways and ribs at opposite ends, substantially as and for the purpose set forth.

2. In a dress or skirt form adapted to be adjusted for varied sizes, the combination, with a central standard and a series of ribs arranged around said standard, of one or more series of adjusting-levers centrally pivoted to a movable collar, one end of said levers connecting with the said ribs and the opposite end with inclined guideways, substantially as 40 described, and for the purpose set forth.

3. In a dress-form, the combination, with a central standard and a series of sections arranged around said standard, of an upper and lower series of levers centrally pivoted on adjustable collars and having connection at one end with the said sections and at their opposite ends operating in inclined guideways located in plates or flanges projecting from the said standard, and a scale, substantially as described, and for the purpose set forth.

JOSEPH R. HEBERT.
